CLAIM

The ornamental design for a low temperature vacuum cooker for gas oven range, as shown and described.

DESCRIPTION

1. Low temperature vacuum cooker for gas oven range
1.1 is a top, front, and left side perspective view of a low temperature vacuum cooker for gas oven range showing our new design;
1.2 is a front elevation view thereof;
1.3 is a rear elevation view thereof;
1.4 is a left side elevation view thereof;
1.5 is a right side elevation view thereof;
1.6 is a top plan view thereof;
1.7 is a bottom plan view thereof; and
1.8 is a top, front, and left side perspective view thereof as installed in an exemplary gas oven range.

(Continued)

The broken line showing of the gas oven range is provided for the purpose of illustrating environmental structure and forms no part of the claimed design.
